US00D994964S

(12) **United States Design Patent** (10) **Patent No.:** **US D994,964 S**
(45) **Date of Patent:** **** Aug. 8, 2023**

(54) **LAMP POLE**

(71) Applicant: **Shanghai YalaMaita Technology Co., Ltd.**, Shanghai (CN)

(72) Inventor: **Yazi Chen**, Yangzhou (CN)

(73) Assignee: **Shanghai YalaMaita Technology Co., Ltd.**, Shanghai (CN)

(**) Term: **15 Years**

(21) Appl. No.: **29/889,868**

(22) Filed: **Apr. 18, 2023**

(30) **Foreign Application Priority Data**

Mar. 31, 2023 (CN) 202330167052.8

(51) **LOC (14) Cl.** **26-05**

(52) **U.S. Cl.**

USPC **D26/138**; D26/145

(57) **CLAIM**

The ornamental design for a lamp pole, as shown and described.

DESCRIPTION

FIG. 1 is a front perspective view of a lamp pole, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The thin broken lines in the drawings illustrate the portions of the lamp pole, which form no part of the claimed design.

1 Claim, 8 Drawing Sheets
